[57] CLAIM

The ornamental design for a top for a lavatory or similar article, substantially as shown and described.

DESCRIPTION

FIG. 1 is a front elevational view of a top for a lavatory embodying my new design;

FIG. 2 is a top plan view thereof;

FIG. 3 is a right side elevational view thereof, the left side being a mirror image of the right side shown;

FIG. 4 is a rear elevational view thereof;

FIG. 5 is a bottom plan view thereof;

FIG. 6 is a sectional elevational view taken along the line 6—6 of FIG. 2; and

FIG. 7 is a sectional view taken along line 7—7 of FIG. 2.

The broken line representation of a lavatory bowl in FIGS. 1 through 7 is for purposes of illustration only.
